UNITED STATES PATENT OFFICE.

AMOS G. FITZ, OF AUBURN, MAINE, ASSIGNOR TO FITZ-EMPIRE DOUBLE PIVOT LAST COMPANY, OF AUBURN, MAINE, A CORPORATION OF MAINE.

LAST.

1,110,917.

Specification of Letters Patent. Patented Sept. 16, 1914.

Application filed April 9, 1913. Serial No. 759,840.

To all whom it may concern:

Be it known that I, AMOS G. FITZ, a citizen of the United States, and a resident of Auburn, in the county of Androscoggin and State of Maine, have invented certain new and useful Improvements in Lasts, of which the following is a specification.

This invention relates to improvements in lasts which are divided transversely and have their parts bonded together by means of links, hinges or other devices, and it relates particularly to means for rigidly locking the parts of the last in lengthened or operative position. I have shown the invention as applied to a last divided and bonded in the manner shown in my Letters Patent No. 909,388, dated January 12, 1909.

The object of the present invention is to so arrange the interlocking parts relative to each other, to the bonding links and to the last parts that the maximum resistance is afforded to any tendency of the last to collapse downwardly or upwardly under the pressures to which the last is subjected in the manufacture of shoes, and to so arrange the contacting surfaces of the interlocking parts that any wear will be automatically taken up in order that the last parts shall always be in close contact when locked together.

In the drawings herewith accompanying and making a part of this application, Figure 1 is a side elevation with parts broken out, of a last with my invention applied thereto; Fig. 2 is a detail side view of the movable interlocking member; Fig. 3 is a detail side view of the other interlocking member; and Fig. 4 is a detail edge view of the member shown in Fig. 2.

In said drawings A represents the fore part and B the heel part of a transversely divided last. The adjacent ends of the last are provided with registering kerfs C and D, one, C, in the fore part and the other, D, in the heel part. In said kerfs the bonding devices O are located. Preferably in the same kerfs because only one cut is necessary, lessening the work and impairing less the strength of the last, are located interlocking members E and F, one E, secured in the fore part of the last, and the other F pivotally mounted in the heel part, and the same pivot pins may support both the bonding devices and the interlocking members. The interlocking device E is held in place by pins G

and H, the pin H passing through an elongated slot I, said slot being elongated to accommodate any slight variation in the distance between pins G and H, thus facilitating the assembling of the parts, and at the same time preventing any movement of the member E, the pin H being the same size as the shortest diameter of the slot. The member F is pivotally mounted at its lower extremity upon a pin J and is provided midway with an enlarged pin receiving hole K sufficient to permit limited backward and forward movement of the lever upon its pivot, the movement being limited by a pin J. The member E is provided with an undercut offset shoulder L and is located vertically near the middle of the fore part of the last. The member F is provided with an interlocking shoulder N curved or inclined at a slightly different angle from the shoulder L of the member E when they are in locking engagement, as shown in Fig. 1. The position of the contacting surfaces of the interlocking members, when in locking engagement, are such that the line of pressure of any force tending to collapse the last upwardly falls inside of the pivot J of the movable member, the last being supported on the heel and toe parts, so that such pressure tends to lock the two parts of the last more firmly together, the tendency being to compel the movable member to turn on its pivot toward the toe part. The two interlocking members are prevented from accidental displacement by means of a spring P bearing against the member F and tending constantly to propel it forwardly. It will be noted that any wear of the contacting shoulders or any imperfection in the original making thereof is compensated by the curved or inclined structure of the interlocking parts.

The parts of the last are designed to be returned from shortened to lengthened position by merely moving the heel part rearwardly and downwardly relative to the fore part. To facilitate this movement the upper rear edge P of member E is rounded and the under edge Q of member F is reversely rounded so that the two parts ride one over the other with a single moving point of contact, the member F yielding as the heel part returns until lengthened position is reached, when the spring automatically impels the member F forward into locking position.

Having thus described my invention and its use, I claim:

1. A transversely divided last, a kerf in the adjacent end of each part, the kerfs of the two parts being arranged to register, bonding means pivotally mounted at each end in said last parts, and interlocking members positioned one in each of said kerfs and provided with positively interlocking shoulders, said interlocking members operating independently of said bonding means, one of said members being movable in the part in which it is mounted, said interlocking shoulders being positioned above the pivot point of said movable member.
2. A transversely divided last, a kerf in the adjacent end of each part, bonding means pivotally mounted at each end in said last parts, and interlocking members independent of said bonding means located in said kerfs, said interlocking members being provided with interlocking shoulders ar-

ranged to come into positive locking engagement when the last parts are brought into lengthened position, and with similarly curved guiding surfaces on the edges thereof arranged to have a sliding point of contact when the last parts are unlocked.

3. A transversely divided last, registering kerfs in the adjacent ends of each part, bonding means pivotally mounted at each end in said last parts, interlocking members provided with shoulders arranged to positively interlock when the parts are in lengthened position and with curved guiding edges arranged to have a sliding point of contact when the last parts are in shortened position and a spring tending to force one member toward the other.

AMOS G. FITZ.
